UNITED STATES PATENT OFFICE.

JOHN R. HIRSH, OF SYRACUSE, NEW YORK.

DESIGN FOR A HAT-SUPPORTER.

SPECIFICATION forming part of Design No. 24,469, dated July 16, 1895.

Application filed May 15, 1895. Serial No. 549,442. Term of patent 3½ years.

To all whom it may concern:

Be it known that I, JOHN R. HIRSH, a citizen of the United States, residing in the city of Syracuse, county of Onondaga, and State 5 of New York, have invented and produced a new and original Design for Hat-Supporters, of which the following is a specification, reference being had to the accompanying drawing, in which I show a hat-supporter in isometric elevation, this one view being sufficient to fully illustrate the design.

The leading feature of my design comprises a substantially-vertical body and a cross-arm extending from the point near its upper end, 15 so as to give the device the design of a sacred cross when looked at from a front view.

a is the vertical body, the lower end *a'* being bent inwardly and outwardly, as shown, and the upper end *b* bent over and attached to a cross-arm *b'*. 20

Having described my invention, what I claim, and desire to secure by Letters Patent, is—

The design for a hat supporter, substantially as described and shown. 25

In witness whereof I have hereunto set my hand on this 7th day of May, 1895.

JOHN R. HIRSH.

In presence of—

JESSIE E. MURRAY,
HOWARD P. DENISON.
